UNITED STATES PATENT OFFICE.

WILLIAM M. KECK, OF LOS ANGELES, CALIFORNIA.

BULL AND CALF WHEEL GUDGEON.

1,315,669.

Specification of Letters Patent. Patented Sept. 9, 1919.

Application filed April 1, 1919. Serial No. 286,682.

To all whom it may concern:

Be it known that I, WILLIAM M. KECK, a citizen of the United States, residing at Los Angeles, in the county of Los Angeles and State of California, have invented certain new and useful Improvements in Bull and Calf Wheel Gudgeons, of which the following is a specification.

My invention relates in general to the class of well drilling machinery and apparatus, and especially to the bull wheels and calf-wheels of the derrick.

My invention consists in a novel construction of the hubs, usually termed gudgeons of the calf-wheel and of the bull-wheel both with respect to its tug-wheel member and its brake-wheel member.

These wheels comprise a gudgeon or hub secured on a shaft, a plurality of arms extending, usually, tangentially to the axis of the gudgeon, and rims composed of cants carried by the extremities of the arms.

The object of my invention is to provide a construction of the gudgeons of these wheels, which will give the maximum strength and resistance to strains in the assembled wheels, and will provide for convenient access to the bolts which secure the arms in the channels of the gudgeons, enabling said arms to be fitted, replaced and tightened as required.

Referring to the accompanying drawings—

Figure 1 is an elevation of the bull-wheel comprising the tug-wheel and the brake wheel member. Fig. 2 is an outer face view, broken, of either member. Fig. 3 is a vertical sectional view partly in elevation, enlarged, of the gudgeon of the wheel, taken at right angles to its axis, on the line 3—3 of Fig. 5. Fig. 4 is a section of the same on the line 4—4 of Fig. 3. Fig. 5 is a plan view of the same.

Though my invention is equally applicable to calf-wheels, and bull-wheels, I have herein deemed it necessary to show only the bull-wheel comprising both tug-wheel member and brake-wheel member, as my improved construction is the same in both members and in the calf-wheel.

The gudgeon is a casting comprising spaced sides 1, between which are equidistant webs 2 tangential to the axis and a journal 3 with a flange 4. These parts are one integral casting.

The sides 1 are cut out to leave openings

at 5 slightly above the face surface of each web 2, the openings being preferably on alternate sides therby avoiding weakening of the casting. From one side to the other of the arm channels thus formed, and above said channels are the braces 6 integral with the casting. These braces are curved upwardly to the openings 5, and together with said openings they provide ample space to reach the arm channels.

At the base or inner end of each channel, there is formed in the casting a cross piece 7 which provides a socket for the inner end of the arm.

8 are the arms, in any suitable number, in practice, eight. The inner end of the arm is fitted in the channel, its extremity entering the socket formed by the cross piece 7. Bolts 9 pass through the arm into the web 2. These bolts are easy to reach, through the openings 5 and the curved braces 6, thereby insuring facility in fitting, replacing and tightening the arms. In addition to the bolts, the arms, thus fitted, are adapted to bear the imposed strains, by reason of the underlying webs 2, the sides 1, and the cross pieces 7, which together form channels in which said arms are closely fitted. The bolts 9, therefore, have little or no strain placed upon them, and have no other function than to hold against outward linear movement, thus presenting a decided advantage over the common practice of using the arm holding bolts for also securing the gudgeon to the shaft.

In the present case, the shaft 10 passes into the axis of the gudgeon, and the latter is secured to it by the rivets 11, through the journal flange 4.

12 is the rim of the wheel constructed and secured to the arms 8 in the usual manner of sectional blocks or cants which need no detailed description.

I claim:—

1. A bull or calf-wheel gudgeon comprising a casting having spaced sides with openings, spaced webs between said sides, and cross pieces forming sockets at the web bases, said sides, webs and cross pieces forming channels in which rim-carrying arms are adapted to be fitted and to be bolted to the webs.

2. A bull or calf-wheel gudgeon comprising a casting having spaced sides with openings, spaced webs between said sides, cross pieces forming sockets at the web bases, and

cross braces between the sides under the outer edge of the webs, said sides, webs, cross piece and braces forming accessible channels in which rim-carrying arms are adapted to be fitted and to be bolted to the webs.

3. A bull or calf-wheel gudgeon comprising a casting having spaced sides with openings, spaced webs between said sides, 10 cross pieces forming sockets at the web bases, cross braces between the sides under the outer edge of the webs, and a flanged journal on one of the sides, said sides, webs, cross pieces, and braces forming accessible channels in which rim-carrying arms are 15 adapted to be fitted and to be bolted to the webs, and said flanged journal forming a bearing by which the gudgeon is riveted to a carrying shaft.

20 4. A bull or calf-wheel gudgeon comprising a casting having spaced sides, equidistant webs between said sides, cross pieces forming sockets at the web bases, and cross braces between the sides under the outer edge of the webs, said sides having a cut out portion at opposite sides of alternate webs, 25 said cut out sides, webs, cross pieces and braces forming accessible channels in which rim-carrying arms are adapted to be fitted and to be bolted to the webs.

5. A bull or calf-wheel structure comprising a gudgeon casting with spaced sides, having openings, spaced webs between said sides and cross pieces forming sockets at

the web bases, said webs, sides and sockets 35 forming arm-receiving channels; arms fitted in said channels; bolts securing the arms to the webs; and a rim carried by said arms.

6. A bull or calf-wheel structure comprising 40 a gudgeon casting with spaced sides having openings, spaced webs between said sides, cross pieces forming sockets at the web bases, and cross braces under the outer edge of each web, said sides, webs, cross 45 pieces and braces forming accessible arm receiving channels; arms fitted in said channels; bolts securing the arms to the webs; and a rim carried by the arms.

7. A bull or calf-wheel structure comprising 50 a gudgeon casting with spaced sides having openings, spaced webs between said sides, cross pieces forming sockets at the web bases, cross braces under the outer edge 55 of each web, and a flanged journal on one of the sides; a shaft riveted in the flanged journal; arms fitted on the webs and seated under the cross pieces; bolts securing the arms to the web; and a rim carried by the arms.

60 In testimony whereof I have signed my name to this specification in the presence of two subscribing witnesses.

WILLIAM M. KECK.
